C. P. SATTLER

LOCK

Filed Sept. 1, 1922

INVENTOR

Carl P. Sattler,
By Owen Owen & Crampton,
Atty.

UNITED STATES PATENT OFFICE.

CARL P. SATTLER, OF TOLEDO, OHIO, ASSIGNOR TO THE ROLLAWAY MOTOR COMPANY, OF TOLEDO, OHIO, A CORPORATION OF OHIO.

LOCK.

Application filed September 1, 1922. Serial No. 585,583.

To all whom it may concern:

Be it known that I, CARL P. SATTLER, a citizen of the United States, and a resident of Toledo, in the county of Lucas and 5 State of Ohio, have made an Invention App- pertaining to a Lock; and I do hereby de- 60clare the following to be a full, clear, and exact description of the invention, such as will enable others skilled in the art to 10 which it appertains to make and use the same, reference being had to the accompa- 65nying drawings, and to the characters of reference marked thereon, which form a part of this specification.

15 This invention relates to locks and is primarily intended for use in locking chains for the spare tires of automobiles, but is not restricted to such use.

The object of the invention is the pro- 20 vision of a small, simple and inexpensive lock of the character described, which is practically proof against breaking or un- 25authorized opening, and which engages a chain in such a manner as to render it impossible for unauthorized persons to 30 release it from the lock when the parts there- 35of are in locked relation, except by breaking the lock or cutting the chain links, both of which parts are hardened to guard against such action.

The invention is fully described in the following specification, and while, in its broader aspect, it is capable of embodiment in numerous forms, a preferred embodiment 35 thereof is illustrated in the accompanying drawings, in which,—

Figure 1 is a side elevation of the lock embodying the invention in locking engagement with the ends of the chain, which is 40 only fragmentarily shown. Fig. 2 is a central longitudinal section of the lock in locking engagement with the chain, taken on the line 2—2 in Fig. 6. Fig. 3 is a fragmentary view of the lock with parts of the 45 socket member and of the lock barrel broken away. Fig. 4 is a central longitudinal section of the lock with the parts in locking position taken on the line 4—4 in Fig. 6. Fig. 5 is a side elevation of the lock with 50 a part of the socket member broken away. Figs. 6 and 7 are sections on the lines 6—6 and 7—7, respectively, in Fig. 1, and Fig. 8 is a section on the line 8—8 in Fig. 2.

Referring to the drawings, 1 designates 55 the socket member of the lock, 2 the stud

member thereof for insertion into the socket member, and 3 a chain section, one end of which is engaged to the socket member and the other to the stud member of the lock, as hereinafter described.

The socket member 1 is of elongated form and has a socket 4, in the present instance of cylindrical form, provided longitudinally therein, being open at one end of the member and having its bottom disposed adjacent to the opposite end of the member. The stud member 2 is intended to releasably fit into the outer or open end portion of the socket 4 and is provided at its inner end with a diagonal or cross groove 5 and adjacent to such end with a circumferential groove 6 in communication with the ends of the groove 5. A locking pin 7 is provided on the inner wall of the socket member 1 adjacent to its outer or open end in position 70 to pass through either end of the groove 5, when in register therewith, and into the locking groove 6 when the stud 2 is inserted into the socket member. A relative turning of the members 1 and 2 from this inserting position will dispose the pin 7 within the groove 6 between the ends of the groove 5, thus preventing a withdrawal of the stud from the socket member until, of course, the stud has been again turned to 80 place either end of the groove 5 in register with the pin 7.

The locking means employed, in the present instance, is of the cylinder lock type and includes a cylindrical barrel 8 which is set 90 into the socket member through an opening 9 in one side thereof with its axis at right angles to the axis of the socket member, the lock being secured against removal from the socket member by a hardened pin 10 which 95 is inserted into a side opening in the barrel 8 through a registering opening in a side of the socket member. The outer end of the pin is cut off flush with the outer side of the socket member to prevent gripping of the pin to withdraw it from engagement with the barrel. The cylinder member 11 of the locking means is adapted to receive and be turned by a key 12, and a turning 100 of the key within the lock effects a retraction of the bolt pin 13 within the lock barrel, said pin being spring pressed to normally hold the same projected, as well understood in the construction of locking means of this character. The bolt pin 13 projects from a 110

side of the barrel 8 lengthwise of the socket member in position to enter the groove 5 of the stud member at one side of the stud member axis when the stud member has been 5 inserted into the socket member and turned to place the groove in receiving register therewith. The pins 7 and 13, in the present instance, are placed at an angle to each other with respect to the socket axis so that 10 when the pin 7 is in engagement with the stud groove 6 it will be necessary to turn the stud to place the pin 7 at a point therein intermediate the ends of the groove 5 when such groove is in receiving register with the 15 pin 13. It is thus evident that the engagement of the pin 7 within the groove 6 will prevent a withdrawing of the stud member 2 from the socket member 1, except when such pin is in register with an end of 20 the groove 5, and that the engagement of the bolt-pin 13 within the groove 5 will prevent a turning of the stud 2 to releasing position, thereby effectually locking the stud and socket members together.

25 The bolt-pin 13 is normally held in projected position by a spring and is retracted by a turning of the key 12 when inserted in the cylinder 11, as well understood in the art. Upon an insertion of the stud 2 into 30 the socket member it is turned to cause the pin 7 to find either end of the slot 5 to enter therethrough into the groove 6, and the bolt-pin 13 is then bearing against the end of the stud 2 at a side of the groove 5 so 35 that an inward pressure on the stud to place the groove 6 into register with the pin 7 will cause a compression of the bolt-pin 13 against its spring. The stud is then turned to move the receiving end of the groove 5 40 from the pin 7 and to place said groove in receiving register with the bolt pin, which then springs outward therein, as shown in Figs. 2, 3 and 8.

45 The chain 3 with which the lock is connected, has a link at one end thereof inserted through a slot 16 in the closed end of the socket member 1 and a pin 17 is inserted into the link through the lock receiving opening 9 of the socket, the lock barrel 8 being removed from the socket for such 50 purpose, and the link is then drawn outward to dispose the pin 17 within the base portion of the socket 4 crosswise of the slot 16 and in engagement with the socket bottom 55 to prevent a withdrawal of the chain link through said slot. When the lock barrel 8 is in position within the slot it coacts with the inner end of the link inserted through the slot 16 to prevent an inward movement 60 of such link sufficient to release the pin 17 from locking engagement therewith, as is apparent. It is evident that this provides a very strong and durable means for connecting one end of the chain to the socket member 65 and prevents a disengagement of the

two except by cutting a chain link in two which is rendered very difficult by the hardened nature of the links, or by removing the lock barrel 8 from the socket, which is rendered exceedingly difficult by reason of the 70 manner of engaging such parts by the hardened pin 10.

The stud member 2 of the lock is provided in its outer end, with respect to the socket member, with a recess 18 in which 75 the link at the opposite end of the chain to that engaged to the socket member 1, is inserted a sufficient distance to permit a cross-pin 19 carried by the stud member to be inserted therethrough. The cross-pin 19 is inserted through a cross opening 20 in the member 2, which opening intersects the recess 18. The pin 19 preferably terminates at its ends flush with the 80 sides of the stud member and is held therein by reason of a tight fit, or in any other suitable manner. When the stud member 2 is in locking engagement with the socket member 1 the pin is disposed within the socket 85 4 so that it is prevented from removal from 90 the stud member by the socket walls, as shown in Fig. 2.

95 It is evident that I have provided a simple and efficient means for locking the ends of a chain or other member together and that it is particularly adapted for engaging and locking together the ends of a chain. It is also evident that when the members 1 and 2 of the lock are in assembled or locked relation the ends of the chain can only be 100 disengaged from the respective members by cutting, which is rendered exceedingly difficult by reason of the hardened nature of the chain links, and the members can only be released by the insertion and turning of a 105 proper key 12 in the cylinder lock to withdraw the bolt-pin 13.

110 The lock is exceedingly simple and inexpensive from a manufacturing standpoint as both members 1 and 2 thereof may be easily made and one end of the chain may be easily and quickly engaged to the socket member before mounting the locking barrel 8 therein, as is apparent, and the other end of the chain may be easily and quickly engaged to the stud member 2 when removed from the socket member.

115 I wish it understood that my invention is not limited to any specific construction, arrangement or form of the parts, as it is capable of embodiment in numerous forms without departing from the spirit of the claims.

120 Having thus described my invention, what I claim as new, and desire to secure by Letters Patent, is,—

125 1. A lock of the class described having 130 stud and socket members capable of insertion one within the other and of relative rotary movements when interengaged, the

stud member having a groove in its circumference with an outlet notch therefrom and the socket member having a pin projecting inwardly therefrom for engagement within the groove when the members are interengaged, the pin preventing a separation of the members except when in register with the release notch of the stud, and locking means carried by the socket member for engaging and locking the stud member against turning relative to the socket member to pin releasing position and being manually operable to release the stud member.

2. In a lock of the class described, a socket member having a transversely projecting pin therein and an opening in a side thereof, a stud member for projecting longitudinally into the open end of the socket and having a cross groove in its inner end and circumferential groove in communication with the cross groove for receiving the pin through the communicating cross groove, the pin and circumferential groove having interlocking engagement to prevent a withdrawal of the stud member from the socket member when the cross groove is moved out of register with the pin, and locking means inserted into the socket member through the side opening thereof and having a manually controlled bolt pin for engagement with the inner end of the stud member to prevent a turning thereof from interlocking relation to the socket member pin.

3. In a lock of the class described, a socket member having an opening in its side and a slot through its closed end, a link projected through the slot, a pin introduced into the socket member through the side opening thereof and inserted through the link within the socket member to prevent a withdrawal of the link therefrom, means closing the side opening of the socket member, and means in releasable interlocked engagement with the open end of the socket member.

4. In a lock of the class described, a socket member having a slot through its bottom and an opening in its side, a stud member for insertion within the open end of the socket member for interlocking engagement therewith, a link inserted through the slot in the socket member bottom, a pin introduced into the socket member through a side opening thereof and inserted through the link to prevent withdrawal thereof from the socket member slot, means closing the side opening of the socket member and operable to releasably lock the socket and stud members together, the stud member having a recess in its outer end and an intersecting cross opening, a link projected into the recess, and a pin inserted into the cross opening and through the link and having its ends covered and protected by the side wall of

the socket when the socket and stud members are interengaged.

5. In combination, a chain section, a socket member having a slot in its bottom for receiving an end link of the chain and having an opening in a side thereof, a pin disposed within the base portion of the socket and inserted through the link to prevent its withdrawal from the socket member, a stud member for insertion into the socket member and for turning in locking engagement therewith, the stud member having a recess in its outer end and a cross opening, which latter is covered by the side wall of the socket member when inserted therein, an end link of the chain inserted into said recess, a pin inserted into the cross opening through the link to retain it in the recess, and manually controlled means disposed within the socket member and closing the side opening thereof for preventing a relative turning of the socket and stud members from interlocking relation.

6. In combination, a socket having a slot through its bottom and a side opening, a chain having an end link thereof inserted through the bottom slot of the member, a pin engaging the link within the member and preventing withdrawal of the link from the member, a stud member at the opposite end of the chain for insertion into the open end of the socket member for interlocking engagement therewith, and means closing the side opening of the member and preventing access to the link holding pin.

7. In combination, a socket having a slot through its bottom and a side opening, a chain having an end link thereof inserted through the bottom slot of the member, a pin engaging the link within the member and preventing withdrawal of the link from the member, a stud member at the opposite end of the chain for insertion into the open end of the socket member for interlocking engagement therewith, and means closing the side opening of the member and preventing access to the link holding pin, and manually operable to releasably engage the stud member and retain it in locking engagement with the socket member.

8. In combination, a socket member, a plug for insertion into the socket member and adapted to have releasable interlocking engagement therewith, and a pin inserted crosswise into the stud member and enclosed by the socket member when the stud member is in interlocking relation thereto, and a chain having a link thereof engaged to the stud member by the pin.

In testimony whereof I have hereunto signed my name to this specification.

CARL P. SATTLER.
